CEMENT, MASONRY, AND STEEL
CONSTRUCTION

John James O'Reilly, Woodside, N. Y.

Application January 9, 1929, Serial No. 331,308

11 Claims. (Cl. 72—1)

This invention relates to improved structural members and methods and has for its primary object to provide a very simple and serviceable means whereby said improved structural members and methods may be applied to building construction to effect improved architectural and structural results with great economy.

It is a more particular object of my invention to provide large units of concrete, metals, stone, and wood and combinations thereof while providing for the field assembly of same by means of welding thus allowing for the completion of a building within a fraction of the time ordinarily required.

My invention also contemplates providing large standardized structural units of welded metal plates for easy assembly in the field by welding thus providing a structural frame which may be quickly completed with incidental finishing materials.

Another object of my invention is to provide a quick method of assembling large exterior wall units of partly prefireproofed metal with large standardized interior units of structural metal at a building site.

A still further object of my invention is to provide a quick and easy method of assembling large partly prefireproofed metal units with other incidental materials to complete a building structure.

With the above and other objects in view the invention consists in the improved structural members and methods, and in the form, construction, and relative arrangement of the various parts as will be hereinafter more particularly described, illustrated in the accompanying drawings, and subsequently incorporated in the subjoined claims.

In the drawings in which I have shown various embodiments of my invention:

Figure 1 is an isometric diagram showing the improved structural members in conjunction with ordinary incidental materials.

Figure 2 is an isometric view of one half of an improved structural member.

Figure 3 is a full plan view of another improved structural member.

Figure 4 is an elevation of still another type of improved structural member.

Figure 5 is a fragmentary side elevation of an embodiment of Figure 2.

Figure 6 is a horizontal sectional view of improved roof members.

Figure 7 is a plan of Figure 6.

Figure 8 is a detailed plan of part of Figure 7.

Figure 9 is a detailed plan of part of Figure 8.

Figure 10 is a vertical section, partly isometric at the upper part, showing the field assembly of an improved structural wall and floor member.

Figure 11 is a fragmentary vertical section showing the field assembly of an improved structural wall member, similar to the one shown in Figure 10, with an embodiment of the improved structural floor member.

Figure 12 is an isometric diagram showing the location of builtin nailing or welding grounds for the erection of trim, etc., and also the metal framing employed in an improved structural member containing a full door opening.

Figure 13 is a fragmentary sectional view of the field assembly of an improved structural floor member with an improved structural partition member above and below, showing also builtin pipes and the method of field assembly used for same.

Figure 14 is a section in plan of the side jamb of an opening, or a section in elevation of the head jamb of an opening, showing the method of applying trim in the shop or field.

Figure 15 is a fragmentary plan view showing the method used for framing out a pipe pocket for a field connection.

Figure 16 is a section through Figure 15 along the broken line A—A.

Figure 17 is a fragmentary sectional view showing the method used for applying trim through the use of builtin welding grounds.

Figure 18 is a sectional diagram of a complete flight of stairs.

Figure 19 is a plan view of a metalbacked wood stair tread face downward.

Figure 20 is a fragmentary detailed view of Figure 18.

Figure 21 is a face plan view of a strip of metalbacked parquet flooring.

Figure 22 is a fragmentary sectional detail of two improved structural members showing the method of field assembly and the method used for connecting electric conduits.

Figure 23 is a horizontal sectional view showing the method of fastening metalbacked wood floors or trim by means of welding grounds.

Referring in detail to the drawings, and more particularly to Figure 1, the symbol 40 indicates an ordinary sidewalk made in the usual manner. 41 indicates an open areaway made in the usual manner. 42 indicates a lefthand foundation footing, 43 indicates a cellar floor, and 44 indicates a righthand foundation footing. Nothing new or patentable is claimed for the construc-

tion of the sidewalk, open areaway, foundation footings, or cellar floor, they are shown in the diagram to help orient the drawing and complete the view.

- 5 In Figure 1—*a1* and *a2* indicate improved structural cellar wall units containing the full window opening *p1* and *p2* respectively. *a3*, *a7*, and *a12* are improved structural floor members, *a7* containing the half stairwell opening indicated by *p6*. *a4*, *a6*, *a8*, and *a11* indicate improved structural wall members containing the half door opening *p3*, the half window opening *p7*, and the full window openings *p5* and *p9*. *a5*, *a10*, and *a9* indicate improved structural interior partition members, containing the full door opening *p4* and the half door opening *p8*. *a13*, *a14*, and *a15* are improved structural attic members. *a16* and *a17* indicate improved structural roof members, *a17* containing the half dormer opening *p10*.

10 In field assembly the units shown in the diagram Figure 1 are erected in numerical order, as follows:

15 The foundation footings (42 and 44) having been fashioned in the usual manner, and covered with a grout of fresh cement, the cellar wall unit (*a1*) is placed in the position indicated in Figure 1 and then the cellar wall unit (*a2*) is placed in position as shown. Similar units are 20 put into position to complete the cellar walls.

25 When the cellar walls have been completed the floor unit (*a3*) is placed in the position shown and similar units are put into position to complete the first floor.

30 35 When the floor units have been all placed into position and fastened the wall unit (*a4*), the partition unit (*a5*), and the wall unit (*a6*) are placed into the position indicated in Figure 1 and similar units are put into position to complete the first floor walls and interior partitions.

40 45 The floor unit (*a7*) is placed in the position indicated and similar units used to complete the second floor. Then the second floor exterior wall and interior partition units (*a8*, *a9*, *a10*, and *a11*) are placed into position together with similar units to complete the second floor work. The attic floor unit (*a12*) is then placed in the 50 position indicated in Figure 1 and similar units placed to complete the attic floor, after which the attic units (*a13*, *a14*, and *a15*) are placed into the position indicated in Figure 1 and similar units placed to complete the interior attic work. The roof units (*a16* and *a17*) are placed into the position indicated in Figure 1 55 after the rest of the structure has been completed and together with similar roof units serve to complete the structure.

60 The field fastening of all of the improved structural members is accomplished by electric arc welding, and the details of each unit and the exact method of fastening will be more particularly described in referring to the following drawings.

65 Figure 2 is a view of one half of the improved structural floor member *a3*, Figure 1, in which *b4* indicates a metal floor joist, *b2* indicates a header or cross framing member, *b3* indicates a lateral brace, and *W* indicates welding wherever the metal plates come into exposed 70 contact with each other. The interior partition unit (*a9*) and the attic units (*a13* and *a14*) are made in a similar manner, except that *b4* would indicate a partition stud, *b2* a sill or plate, and *b3* would indicate a lateral brace.

75 The attic floor unit (*a12*) is likewise made in

a similar manner to *a3*—Figure 2. The shading at the near end of Figure 2 indicates the line of division only one half of the unit being shown in the drawings.

80 Figure 3 is a detailed plan view of the improved structural floor member (*a7*), in which *b4* indicates a floor joist, *b2* a header or cross framing member, and *b3* indicates a lateral brace. *b5* indicates a header for framing out the half stairwell opening (*p6*). The exterior 10 wall unit (*a8*) is constructed in a like manner except that the symbol *b4* would indicate a wall stud, *b2* a sill or plate, *b3* a lateral brace, and *b5* a header for framing out the half window opening *p7*.

15 20 Figure 4 is a detailed elevation of the improved structural wall member (*a6*) showing the method of framing around the full window opening (*p5*). The cellar wall units (*a1* and *a2*) are constructed in a similar manner except that the window openings (*p1* and *p2*) are relatively smaller. The second floor wall unit (*a11*) is exactly similar to *a6*.

25 30 Figure 5 is a fragmentary side elevation of the improved structural roof member (*a17*), showing the mitering of the cross framing plate (*b2*) to effect a mitred contact at the peak of the roof. *a11* is otherwise similar to *a7* as shown in Figure 3. *a16* is similar to *a17* except that the framing out for the half dormer opening is omitted. *a15* is exactly similar to *a16* except that it has a mitred connection at both ends.

35 40 The first floor exterior wall unit (*a4*) and the second floor interior partition unit (*a10*) are exactly similar to Figure 3 without the framing in the upper right hand corner as indicated by the broken line O—O, Figure 3.

45 50 A detailed diagram of the improved structural interior partition unit (*a5*) is shown in Figure 12.

55 All of the above mentioned members are formed by welding ordinary metal plates together wherever the metal of one plate comes into exposed contact with the metal of another plate. The field assembly is likewise accomplished by welding adjacent units to each other in the relative position indicated in the diagram Figure 1.

60 65 Figures 6, 7, 8, and 9 indicate the fabrication and field assembly of roofing shingles also by welding.

70 75 In Figure 9, *20* indicates that portion of an individual shingle exposed to the weather, and *21* indicates that portion of an individual shingle not exposed or lapped by adjacent shingles.

80 85 Figure 8 indicates the shop assembly of a plurality of individual shingles to form a supershingle by means of welding. *20a* indicates the portion of a supershingle exposed to the weather and *20b* indicates that portion of a supershingle not exposed to the weather or lapped. The shop assembly is accomplished by laying out the supershingle pattern on a platform and welding the individual shingles together from the back. 90 The individual shingles are of metal, preferably galvanized iron dipped into paint and otherwise treated for varied colored and textural effects before assembly.

95 100 Figures 6 and 7 indicate the field assembly of four supershingles (*20a*—*21a*—*22a*—*23a*) with the ridge cap, indicated by *24c*, to complete one half of a roof. The other half of the roof is exactly similar, except that dormer openings may be left uncovered and no additional 105

ridge cap is required. The ridge cap is a narrow supershingle bent at right angles as shown. The broken outline of an improved structural roof member, indicated by *a17*, is shown beneath the supershingles in Figure 7, and in the same figure *24e* indicates a projecting eave. Figure 6 indicates clearly how the supershingles are placed into position for field welding, the lower one (*20a*) first, then *21a*, *22a*, and *23a* in order. The ridge cap is not placed into position until the supershingles on the opposing pitch of the roof have been welded in place. The field welding of the supershingles is accomplished from underneath in the attic, and the ridge cap welding being exposed is carefully protected from the weather. It will be understood that metal other than galvanized iron may be used to form the supershingles, and that brazing or soldering may likewise be used for fastening purposes.

To obtain certain architectural, structural, and economic results the improved structural members (*a1* to *a17*, inclusive) may be (partly) prefirereproofed before field assembly. The method of field welding for prefirereproofed metal members is likewise described and covered in above mentioned application and nothing new is disclosed in this application for the process of arc welding through open joints in stonework. Figure 10 shows the method of assembly used in the field for a prefirereproofed wall member (*Xa4*) and the improved structural floor member *a1*. *Fp* indicates the prefirereproofing accomplished in the shop. *W* indicates field welding. In the lower half the welding is accomplished, as described in the previously mentioned application, through the open joints, indicated by *W*—*W*. In the upper part of the figure the metal plate *b2* is welded to the exposed wall studding (*b4*) in the field.

Figure 11 shows the method used for assembling a prefirereproofed wall member (*Xa4*) and a prefirereproofed floor member (*Xa7*) by welding them together in the field as indicated at *W*. Figure 12 indicates the location of builtin welding or nailing grounds for picture mouldings, trim around an opening, base, door saddles or sills, and floors. The framing of the improved structural interior partition member (*a5*) is also clearly indicated. The symbol *G* indicates a welding ground.

Figure 14 shows in section the location and arrangement of the builtin grounds around a window or door opening and *W* indicates the field welding or shop welding which is accomplished through a hole in the trim as described hereinafter. *T1* indicates a rabbeted jamb and *T8* standing trim.

Figures 13, 15, and 16 refer to builtin piping, in which *1p* indicates a length of pipe builtin a prefirereproofed structural member. *X3a* and *X40a* Figure 15 indicate prefirereproofed structural floor members, placed side by side and welded together from above and below through open vertical joints similar to the open horizontal joints indicated at the lower part of Figure 10. *WAB* indicates field welding along the line of the adjacent floor joists both above and below the plane of the fragmentary view shown in Figure 15. In fabricating the structural members *X3a* and *X40a* the continuity of the floor joists is broken as shown and spliced with the splice joists *b6* thus forming a pocket *p12* when the adjacent joists are brought together in the process of field assembly. A length

of pipe is indicated by *1p* in each floor member at right angles to the floor joists and passing through a hole provided in the splice plates *b6*. Field assembly of the structural floor members brings the open ends of the pipes directly opposite each other and they are welded together, or the pocket *p12* is filled with lead to caulk the joint, or in the case of brass pipe brazing is used to make a tight joint.

Figure 16 is a sectional view of Figure 15 along the broken line A—A, and shows the pipe pocket (*p12*) more clearly. *b7* indicates a small plate which is welded to the bottom of the pocket to permit caulking without waste. Figure 13 indicates the method used for exposing the ends of builtin pipes for a cross connection. *X3a* is a prefirereproofed floor member, *X5a* is a prefirereproofed partition member above, and *X22a* indicates the same below. In field assembly the open ends of the builtin pipes (*1p*) are brought directly over each other and welded together through the open joints as indicated by *W*. It will be noted that the pocket (*p12*), as indicated in Figures 15 and 16, will serve as an ideal expansion fitting for heating pipes. When the ends of the pipes which enter the pocket are kept slightly apart, and not fastened together, expansion and contraction is automatically taken care of by the vibration of the splice joists *b6*. In order to confine the contents of heating pipes within the pocket (*p12*) a plate similar to *b7* is fastened to the top of said pocket and the entire pocket welded air tight.

Through leaving open ends of pipe projecting thru the prefirereproofed members as indicated in Figure 13 it is a simple matter to connect other pipes thereto simply by welding close to the face of the unit and covering the weld with an escutcheon. In this manner the exposed piping may be extended to the boiler, radiators, 40 plumbing fixtures, etc.

Figure 19 shows a metal plate, indicated by *m2*, with six holes punched through same as indicated by *h3*. An ordinary wooden stair tread is placed face downward on a platform 45 and a metal plate similar to that shown in Figure 19 is placed over the back of same and fastened thereto by means of wood screws passed through the holes *h3*. A stair riser of metal-backed wood is fashioned in a similar manner, 50 likewise a wall stringer, except that the wood for the wall stringer is profiled to follow the line of the tread and the riser in the assembled stair as shown in Figure 20. In Figure 18—*S* indicates a wall stringer, *S2* a stair tread, *S3* a stair 55 riser, and *S4* indicates a base stringer. Figure 20 shows a detailed view of the shop assembly of an entire stair, *m4* indicates the exposed woodwork and *m2* the concealed metal work. *W* indicates the shop welding of treads to risers. *W5* indicates the shop welding of the treads and risers to the wall stringer. *h2* indicates a welding hole in the concealed part of the stair for fastening the wall stringer to a welding ground 60 builtin the stairwell partition. It will be understood that units of marble may be backed with metal by boring holes in the back of the marble and filling same with fresh cement before inserting the screws through the metal back, and likewise that the complete stair may be formed of 65 welded metal plates and then covered on the exposed portions with welded wire lath and plastic finishing materials. The complete stair in any event is fabricated complete at the shop and installed as a complete unit in the field.

Figure 21 is a face plan of a strip of parquet flooring to the back of which is fastened a metal sheet similar to *m2*, Figure 19. *h2* indicates holes which have been cut in the finished face of the flooring to permit field welding to a built-in ground. Figure 23 indicates the method used for welding steelbacked wood flooring to a built-in floor ground thru the hole *h2*. *m2* indicates the metal backing, *m6* a layer of paper, and *m4* the wood flooring with the false joints, indicated by *V2*, cut into the surface of same to give the effect of parquet, herringbone, etc. The thimble *T12* is used as a temporary shield for the wood and paper during the process of welding. *W* indicates how the metal backing (*m2*) is welded to the builtin floor ground indicated by *G*.

Figure 17 indicates the method used for welding metal trim, in the shop or field, to a builtin ground (*G*). *T7* indicates a fragment of metal trim which is welded (through the hole *h2*—as indicated by *W*) to the builtin ground (*G*). To complete the electric circuit for welding the builtin grounds are always welded to some part of the structural frame, such as *b4*—Fig. 17.

When the field welding is completed all welding points are filled with materials and matched to the adjacent surfaces.

Figure 22 indicates the method used for splicing lengths of electric conduit which are built-in the various prefireproofed members at the shop. The left hand floor member, indicated by *X3a*, and the right hand floor member, indicated by *X40a*, are to be placed together and welded to each other through the open joints so formed as indicated by *W*—*W*. The flexible conduit, indicated by *b4*, and the junction box, indicated by *Jb*, are first welded together as indicated by *W*, and when the two units (*X3a* and *X40a*) are brought together for welding the junction box and the excess conduit are placed in the recess indicated by *re*. The shop installation of the conduit and fixture boxes, etc., in the members is accomplished in the same manner as ordinarily employed for concrete arch work and nothing new or patentable is claimed for it.

When the prefireproofed metal members are used exclusively with welding shingles to complete a structure or small dwelling the interior surfaces are finished at the shop with colored textured monolithic facings as provided in the hereinbefore mentioned pending application. In the field the joints are pointed or filled with similar materials to provide an unbroken surface. When the field welding has been completed, and the boiler, radiators, plumbing fixtures, and lighting fixtures connected, and the welding points covered or patched the house is completed. No exterior or interior painting is required, as owing to the method and the exactness thereof, even the doors and the window frames and sash, whether of metal or of wood, are made to an exact size and shop finished. All of the materials are shop cured and there is no dampness in the new structure. It is ready for immediate occupancy.

It will readily be seen from the foregoing description considered in connection with the accompanying drawings that the construction and methods and manner of use of the several illustrated embodiments will be clearly and fully understood. In view of the simplicity of the improved structural members and the methods involved and their architectural, structural, and economic importance they will be of great utility

in the construction of all types of structures. I have disclosed herein various forms of my improved structural members and the methods involved which I consider of the most practical importance. Nevertheless it is to be understood that the invention, in view of the wide scope of architectural and structural requirements, may also be exemplified in numerous other alternative constructions, and I therefore reserve the privilege of adopting all such legitimate changes as may be fairly embodied within the spirit and scope of the invention as claimed.

I claim,

1. A building structure comprising an assembly of individual units arranged and disposed in precise architectural and structural relation to form the enclosed useable spaces of the said structure, certain of the aforesaid units containing each a welding band with spaced supporting members fastened thereto, also factory applied surfacing materials on two of its opposite architectural surfaces concealing a field connected piping system extended for service throughout the building, reciprocal lateral support of the aforesaid welding band and the spaced supporting members fastened thereto by other necessary parts of the structure in lieu of their being as formerly specially shaped in the shop for self bracing laterally, and a welded continuity of the aforesaid units and other necessary parts providing a maximum of reciprocal support for a minimum of material outlay.

2. A building unit comprising a welding band with spaced metal plate supporting members welded thereto, surfacing materials enclosing piping concealed in the interior of the said unit, offsets in the aforesaid welding band exposing for field fastening purposes the open ends of the aforesaid concealed piping, and means in the unit for assembling same in welded continuity and precise architectural and structural relation with other similar units in a building structure.

3. A building structure comprising an assembly of individual units arranged and disposed in precise relation to form the useable spaces of the said structure, each of the aforesaid individual units containing a separate structural frame comprising a welding band with spaced supporting members fastened thereto also factory applied surfacing materials enclosing field connected piping concealed in the interior of the said unit, and a welded continuity of all of the aforesaid units throughout the structure.

4. A building structure comprising an assembly of individual units arranged and disposed in precise architectural and structural relation to form the walls and the floors and the partitions and the roof of the said structure, certain of the aforesaid units containing each a separate structural frame comprising a welding band with spaced supporting members fastened thereto also surfacing materials enclosing service piping and insulating materials concealed in the interior of the said units, and a welded continuity of all of the aforesaid units throughout the structure.

5. A building structure comprising an assembly of individual units arranged and disposed in precise architectural and structural relation to form the useable spaces of a complete dwelling, certain of the aforesaid units containing each a separate structural frame comprising a welding band forming a natural flat bed around the side and end edges of each of the said units for safe ultra speedy field assembly.

purposes and spaced supporting members fastened to the interior of each of the said welding bands for the purpose of providing very large units for field setting having light and economical closely spaced supporting members, roofing bracing laterally supporting members of the structure in lieu of their being as formerly specially shaped in a form such as an angle for self bracing laterally, other features as hereinbefore 5 newly disclosed optional, and a welded continuity of all of the aforesaid units and roofing and optional features throughout the finished dwelling.

6. A building structure comprising an assembly of individual units arranged and disposed in precise architectural and structural relation to form the useable spaces of the said structure, certain of the aforesaid units containing each a separate structural frame comprising a welding band forming a natural flat bed on the side and the end edges of each of the said units for safe ultra speedy field assembly purposes also spaced supporting members fastened to the interior of each of the said welding bands for the 10 purpose of providing very large field units having closely spaced supporting members, flooring bracing laterally in push and, pull manner supporting members of the structure in lieu of their being as formerly specially shaped in a form such as a channel for self bracing laterally, and a welded continuity of all of the aforesaid 15 units throughout the structure.

7. A building structure comprising an assembly of individual units arranged and disposed in precise architectural and structural relation to form the useable spaces of the said structure, each of the aforesaid units continuing a separate structural frame exactly as disclosed hereinbefore, roofing and interior trim bracing laterally certain supporting members of the said structure, and a welded continuity of all of the aforesaid units and the roofing and the trim throughout the structure.

8. A building structure comprising an assembly of individual units arranged and disposed in precise architectural and structural relation to form the useable spaces of the said structure, each of the aforesaid units continuing a separate structural frame exactly as disclosed hereinbefore, sheathing and flooring bracing laterally certain supporting members of the said struc-

ture, and a welded continuity of all of the aforesaid units and the sheathing and flooring throughout the structure.

9. A building unit comprising metal plate headers forming two opposite ends of the said unit, a plurality of spaced metal plate supporting members fastened to the aforesaid metal plate headers to form a structural frame having cross framing members marking out such as window openings, two separate layers of surfacing materials forming an interior and an exterior wall surface for the main body of the unit, and means in the unit for assembling same in precise architectural and structural relation with other units in a structure.

10. A building unit comprising a welding band with spaced joists or studs fastened thereto, two separate layers of cementitious or like materials moulded in the interior of the said welding band, spaced metal re-inforcement embedded in the cementitious or like materials, one or more offsets in the aforesaid welding band exposing the ends of piping concealed in the unit, and means in the unit for assembling same in precise architectural and structural relation with other similar units in a building structure.

11. The relative steps involved in building a dwelling or the like which comprises the initial step of assembling individual sections above a previously prepared foundation in precise architectural and structural relation substantially as hereinbefore described with the outer surfaces of the said sections disposed in the proper relation to each other to form the enclosed living spaces of the said dwelling or the like, inserting an arc welding electrode between the outer surfaces of each two adjoining sections in turn as soon as they have been properly set and without injury to the said outer surfaces depositing welding beads collectively on the said sections to fasten them together rigidly just back of both outer surfaces of each of the said sections, caulking gas-tight with molten metal or the like around the ends of pipes exposed in exact relation to each other for the purpose between certain of the said sections, and finally filling with surfacing materials the crevices between the aforesaid sections to provide suitable surfaces therefor and to protect the welding deposits in the said crevices.

JOHN JAMES O'REILLY.
